UNITED STATES PATENT OFFICE

2,630,077

LITTER CARRIER

Merle D. Tate, Cannon Falls, Minn.

Application October 18, 1949, Serial No. 122,039

4 Claims. (Cl. 104—178)

1

This invention relates to novel and useful improvements in litter carriers.

An object of this invention is to selectively control the direction of rotation of a shaft, which shaft operates a carriage adapted to support various substances by means of a single movement either in one direction or the other direction of a control mechanism.

Another object of this invention is to provide an improved litter carrier which includes a pair of friction disks operatively connected by a driving element or wheel whereby upon movement of the driving element or wheel from one disk to the other, the direction of operation of the carriage is controlled, and after such movement, the driving element is returned by spring action to the inoperative or out-of-contact relationship with the disks.

Ancillary objects and features will become apparent in the following description of the illustrated form of the invention.

In the drawings:

Figure 1 is an elevational view of the device showing a suggested assembly;

Figure 2 is an enlarged elevational view of a part of the structure shown in Figure 1, portions being broken away in section to illustrate detail of construction;

Figure 3 is a fragmentary plan view of the assembly shown in Figure 1;

Figure 4 is a sectional view taken on the line 4—4 of Figure 3 and in the direction of the arrows; and

Figure 5 is a largely schematic plan view of fragments of the device illustrating the position of the parts or components when the driving element is drivingly connected with one of the disks.

The present invention deals with litter carrier assemblies but may be employed for transporting any suitable article or articles.

In the system, a post or pole 10 is employed at a position remote from that where the litter is collected. A bed generally indicated at 12 is disposed at the position where collection and loading takes place. This bed includes a pair of parallel sides 14 and 16 which may be made of any suitable stock, such as channel iron, and a pair of cross members 18 and 20 connecting the sides. A bracket 24 is disposed on the cross member 18 and has a pivot pin, as the bolt 26, passed therethrough and also through the cross member 18. This mounts the bracket 24 for pivotal movement in a horizontal plane since the axis of the bolt 26 is vertical.

A pair of air braces 30 and 32 are disposed in

2

parallel relationship with the sides 14 and 16 and are fixed to the cross members 20 and 18. An arcuate bar 36 is secured to the ends of the braces 30 and 32 and is accordingly, in a higher plane than the braces.

An extension in the form of a bar 38 is riveted or otherwise rigidly secured to the bracket 24, passing under the curved member 36 but being disposed on the cross member 20.

10 A motor 40 is fixed on the bracket 24 and has a drive shaft 42 extending therefrom. This drive shaft has a friction driving element 44 removably secured thereto for selective driving engagement with the friction disks 46 and 48, respectively.

15 The friction disks are secured in spaced relationship on the shaft 50 which is mounted in bearings 52 and 54, respectively. These bearings are carried by the sides 14 and 16 and are of conventional description.

20 A second shaft 58 is mounted in bearings 60 and 62, the shaft 58 being parallel to the shaft 50. The bearings 60 and 62 are carried by the said sides 14 and 16. A sprocket 64 and a sprocket 66 are secured to the shafts 50 and 58, respectively, and there is a chain 68 entrained around both sprockets. It will be noted at this point that a V-groove pulley-belt arrangement may be employed as an alternative for the sprocket and chain assembly.

25 Vertical standards 76 and 78 are secured at the end of the bed 12 and specifically are secured to the sides 16 and 14. These vertical standards are adapted to be suspended from any suitable structural elements, as the beam schematically shown in Figure 1 and indicated at 80. The vertical standards 79 and 83 are secured to the front ends of the sides 14 and 16 and may be braced as by gusset plate 81 (note Figure 1). These members are also adapted to be suspended from a beam or specially provided structural assembly.

30 A hanger 82 is disposed above and to the side of the bed. This hanger supports a cable or trolley wire 84 by means of the clamp 86 which is secured to one end thereof. The opposite end of the trolley wire 84 has another clamp 86 secured thereto on the rear face or surface of a bracket 88 which is carried by the post 10. This maintains the wire 84 taut and spaced from the bed to the post 10.

35 A carriage generally indicated at 90 is provided. The carriage includes a bucket 92 which has an open top and is employed for the purpose of holding the litter. Means for supporting the carriage on the cable 84 is provided. This means consists of a pair of trolley wheels 94 and 96 which are

55

3

carried by the brackets 97 and 98. These brackets are fixed to the opposite ends of the receptacle 92. Since the trolley wheels 94 and 96 are disposed on the cable 84, the carriage is free to slide from one end thereof to the other.

A single length of cable, rope or the like indicated at 100 is secured at its ends to the ears 102 and 104 which are fixed to the opposite ends of the receptacle 92. This cable 100 is also entrained around the pulleys 108 and 110, respectively, which are supported by the post 10 and bed 12, respectively. The pulley 108 is mounted on a bracket 112 which is secured to the post 10. The pulley 110 is fixed to the shaft 58 for rotative movement therewith. A fibre or rubber liner 116 is disposed on the periphery of the pulley 110 to insure a frictional drive.

In operation the motor 40 is energized. Then, when there is a driving connection between the disk 46 or the disk 48 and the driving element 44, the pulley 110 will be operated. This will cause movement of the carriage toward and away from the bed 12, depending upon whether the drive is through the disk 46 or 48.

In order to cause this selectivity of operation, there is a pair of guides, as the pulleys 120 and 122, respectively, which are fixed to brackets 124 and 126. These brackets are carried by the bed at the end thereof adjacent the junction between the supports 76, 78 and the sides 14, 16. A control rope or cable 128 is secured at one end to a rocker 130 and is entrained over the pulley 120. An identical control rope or cable 132 is entrained over the pulley 122 and has its inner end attached to the same rocker 130. Since the rocker is pivoted to the arm 38, when one or the other of the control cables or ropes are pulled, this movement is reflected in pivotal movement of the bracket 24 and motor 40.

In order to return the motor to such position that the driving element 44 does not engage the disks 46 and 48, resilient means is provided opposing the operation of the bracket 24. This resilient means consists of a spring 136 which is secured at one end to the curved member 36 and secured at its other end to the hook 140. This hook is rigidly secured to the arm 38 so that the load applied to the spring by turning the bracket 24 may cause the bracket to return to a position substantially parallel to the sides 14 and 16.

When the motor is pivoted about its pivot shaft 26, the rollers 150, 151, 152, and 154 are brought into play. These rollers are fixed beneath the motor base or pivot plate 24 for movement therewith. Brake arms 156 and 158 are secured on fixed pivots 160 and 162 carried by a suitable stationary structural member and are engaged by these rollers upon pivotal operation of the motor. The brake arms 156 and 158 are arranged so that the brake lining material at the ends thereof contact the disks 46 and 48, respectively, when the motor is in such position that the driving element 44 is spaced from said disks. However, when the motor is pivotally operated, as to the position shown in Figure 5, the roller 151 engages and pushes the arm 156 to such position that it is spaced from the disk 46. The roller 154 contacts the arm 158 also spacing it from its disk 48. The brake is thereby released, but as soon as the driving element 44 is spaced from either of the disks the brake arms spring back against the disks 46 and 48 firmly through the action of the springs 156 and 158 (Figure 3) which oppose the inward movement of said brake arms.

4

The purpose of the brake is obvious in that it prevents overriding of the carrier bucket and also prevents movement of the bucket which is undesirable, as by sag in the line and as by wind.

Having described the invention, what is claimed as new is:

1. A carrier comprising a post and a mounting bed remote from the post, a carriage, a wire extending from said bed to said post, means secured to said carriage and disposed on said wire supporting said carriage, means separate from said wire and disposed on said bed and operatively connected to opposite sides of said carriage for operating said carriage selectively in opposite directions on said wire, including a shaft mounted on said bed with a first and a second friction disk mounted thereon, and a driving member mounted pivotally on said bed between said disks and engaging said first and second disks selectively to operate said shaft in opposite directions, a motor secured to said driving member, a pivoted bracket supporting said motor on said bed, a pair of guides secured to said bed, a pair of flexible members secured to said bracket, one of the flexible members being entrained over one guide and the other flexible member being entrained over the other guide, the guides being disposed on opposite sides of said bracket whereby pulling one of the flexible members causes pivotal movement of said bracket.

2. A carrier comprising a post and a mounting bed remote from the post, a carriage, a wire extending from said bed to said post, means secured to said carriage and disposed on said wire supporting said carriage, means separate from said wire and disposed on said bed and operatively connected to opposite sides of said carriage for operating said carriage selectively in opposite directions on said wire, including a shaft mounted on said bed with a first and a second friction disk mounted thereon, and a driving member mounted pivotally on said bed between said disks and engaging said first and second disks selectively to operate said shaft in opposite directions, a motor secured to said driving member, a pivoted bracket supporting said motor on said bed, a pair of guides secured to said bed, a pair of flexible members secured to said bracket, one of the flexible members being entrained over one guide and the other flexible member being entrained over the other guide, the guides being disposed on opposite sides of said bracket whereby pulling one of the flexible members causes pivotal movement of said bracket, and a spring reacting on said bracket on said bed opposing the pivotal operation of said bracket.

3. In a device to rotate a shaft, a bed having a vertical pivot, a bracket mounted for pivotal movement on said vertical pivot and supporting a motor, a driving element adapted to be actuated by said motor, at least one spring opposing the pivotal movement of said bracket to return said bracket to a neutral position when said bracket is pivotally displaced from said neutral position, a first friction disk and a second friction disk spaced from said first friction disk, said disks being in parallel position with respect to each other, a shaft located on said bed and having said disks fixed thereto, said element being located between said disks, and means operatively connected with said bracket to swing said bracket pivotally about said pivot so as to engage said driving element selectively with said disks.

4. The device of claim 3 and brake members carried by said bed and including arms, said arms

having their outer ends arranged to contact said disks, and means carried by said bracket and contacting said arms to separate said outer ends of said arms from collectively said first and said second disk in response to pivotal movement of 5 said bracket.
